Primary Examiner — Ian Simmons*Assistant Examiner* — Shannon Morgan(74) *Attorney, Agent, or Firm* — Sand & Sebolt(57) **CLAIM**

The ornamental design for a pet waste scoop assembly, as shown and described.

DESCRIPTION

FIG. 1 is a front perspective view of a pet waste scoop assembly showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines and area within the broken lines shown in FIG. 3 represent portions of the pet waste scoop assembly that form no part of the claimed design.
